Paul E. Werner,
INVENTOR,

BY *C. E. Kammeyer*

ATTORNEY

UNITED STATES PATENT OFFICE.

PAUL E. WERNER, OF KANSAS CITY, MISSOURI.

DESIGN FOR AN ELASTIC VEHICLE-TIRE.

48,509.

Specification for Design.

Patented Feb. 1, 1916.

Application filed November 8, 1915. Serial No. 60,446. Term of patent 3½ years.

To all whom it may concern:

Be it known that I, PAUL E. WERNER, a citizen of the United States, residing at Kansas City, in the county of Jackson and State of Missouri, have invented a new, original, and ornamental Design for Elastic Vehicle-Tires, of which the following is a specification, reference being had to the accompanying drawings, forming part thereof.

In the drawings, Figure 1, is a side elevation of an elastic vehicle tire embodying my invention; and, Fig. 2, is a section on line X of Fig. 1.

I claim:—

The ornamental design for an elastic vehicle tire, as shown.

PAUL E. WERNER.

Copies of this patent may be obtained for five cents each, by addressing the "Commissioner of Patent, Washington, D. C."
